CLAIM

The ornamental design for a button adapter, as shown and described.

DESCRIPTION

FIG. 1 is a top perspective view of a button adapter, according to a first embodiment;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a bottom perspective view thereof;

FIG. 9 is a bottom, front-left exploded view thereof;

FIG. 10 is a bottom, rear-right exploded view thereof;

FIG. 11 is a top, front-right exploded view thereof;

FIG. 12 is a top, rear-left exploded view thereof; and

FIG. 13 is a cross-sectional view thereof, taken in the direction of line 13-13 on FIG. 6.

FIG. 14 is a top perspective view of a button adapter, according to a second embodiment;

FIG. 15 is a front elevation view thereof;

FIG. 16 is a rear elevation view thereof;

FIG. 17 is a left elevation view thereof;

FIG. 18 is a right elevation view thereof;

FIG. 19 is a top plan view thereof;

FIG. 20 is a bottom plan view thereof;

FIG. 21 is a bottom perspective view thereof;

FIG. 22 is a bottom, front-left exploded view thereof;

FIG. 23 is a bottom, rear-right exploded view thereof;

FIG. 24 is a top, front-right exploded view thereof;

FIG. 25 is a top, rear-left exploded view thereof; and,

FIG. 26 is a cross-sectional view thereof, taken in the direction of line 13-13 on FIG. 19.

The broken lines are shown for the purpose of illustrating both parts of the article as well as environmental subject matter. None of the broken lines form part of the claimed design.
